UNITED STATES PATENT OFFICE.

ELIZABETH C. DONALDSON, OF DETROIT, MICHIGAN.

DESIGN FOR A MUSTACHE-GUARD.

SPECIFICATION forming part of Design No. 29,059, dated July 19, 1898.

Application filed March 28, 1898. Serial No. 675,508. Term of patent 14 years.

To all whom it may concern:

Be it known that I, ELIZABETH C. DONALDSON, a citizen of the United States, residing at Detroit, county of Wayne, State of Michigan, have invented and produced a new and original Design for a Mustache-Guard, of which the following is a specification, reference being had to the accompanying drawings, which form a part of this specification.

10 As shown in the drawings, Figure 1 is a view in perspective of a mustache-guard, showing my new design. Fig. 2 is a sectional view thereof, taken on the line 2 2, Fig. 1.

15 The leading feature of my design consists of an elongated body A, curved in cross-section, the body being convexed on the upper surface thereof, as shown in Fig. 2, said body projecting downward from the rear edge thereof toward the front edge thereof, so that 20 the upper and lower edges of the body will be in different horizontal planes. The front edge of said body is cut away on the arc of a circle, the front edge being shorter in outline than the rear edge. The rear edge is made round- 25 ing at its center, as shown at b, and from this

rounded portion b the two curved edges c extend outwardly and terminate in the small abrupt shoulders e. From these shoulders the ends extend outwardly in straight lines g. Extending from the extremities of the body 30 and laterally therebeyond are curved portions or arms a a, each having an upwardly-projecting portion a' and a downwardly-projecting portion a'', said portions spaced the one from the other, said arms forming loops at opposite 35 extremities of the body. The lateral edges of the body have their outline inside said arms, respectively.

Having thus described my invention, what I claim as new, and desire to secure by Letters 40 Patent, is—

The design for a mustache-guard, as shown and described.

In testimony whereof I sign this specification in the presence of two witnesses.

ELIZABETH C. DONALDSON.
